UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

DESIGN FOR LIGHT-TRANSMITTING GLASS.

Application filed October 24, 1921. Serial No. 510,142. Term of patent 14 years.

To all whom it may concern:

Be it known that I, CROMWELL A. B. HALVORSON, Jr., a citizen of the United States, residing at Lynn, in the county of Essex, State of Massachusetts, have invented a new, original, and ornamental Design for Light-Transmitting Glass, of which the following is a specification, reference being had to the accompanying drawing, forming a part thereof.

The drawing is a front elevation of a piece of glass of my design in which the outer surface of the glass is covered with protuberances and depressions.

I claim:

The ornamental design for light-transmitting glass as shown and described.

In witness whereof, I have hereunto set my hand this 20th day of October, 1921.

CROMWELL A. B. HALVORSON, JR.
